W. K. ROGERS,
LENS GRINDING MACHINE.

APPLICATION FILED JUNE 9, 1913. RENEWED FEB. 10, 1914.

1,140,483.

Patented May 25, 1915.

UNITED STATES PATENT OFFICE.

WALTER K. ROGERS, OF TOLEDO, OHIO, ASSIGNOR TO THE ROGERS AUTOMATIC LENS COMPANY, OF TOLEDO, OHIO, A CORPORATION OF OHIO.

LENS-GRINDING MACHINE.

1,140,483.

Specification of Letters Patent. Patented May 25, 1915.

Application filed June 9, 1913, Serial No. 772,573. Renewed February 10, 1914. Serial No. 817,920 1/2.

To all whom it may concern:

Be it known that I, WALTER K. ROGERS, a citizen of the United States, residing at Toledo, in the county of Lucas and State of Ohio, have invented certain new and useful 5 Improvements in Lens-Grinding Machines; and I do hereby declare the following to be a full, clear, and exact description of the invention, such as will enable others skilled in the art to which it appertains to make and 10 use the same.

This invention relates to machines for grinding optical lenses, and it has particular reference to certain improved details of 15 construction found to be essential to the operation of a machine intended for a like purpose for which I was granted Letters Patent of the United States, dated September 10, 1912, Patent No. 1,037,992.

20 In the machine which forms the subject of this application I provide improved means for transmitting rotary movement to the lens block spindle and the tool spindle through the agency of spiral gears, whereby 25 all lost motion is eliminated; improved means for subjecting the lens block to tension in the direction of the grinding tool, with means for increasing or diminishing the tension; improved means for adjusting 30 the lens block relative to the grinding tool; and improved means for varying the swinging movement of the jointed spindle carrying the lens block.

35 In carrying out my invention I employ the novel combination, arrangement and details of construction hereinafter shown, described and claimed.

40 In the accompanying drawings Figure 1 is a front view of a lens grinding machine embodying my improvements; Fig. 2 is a 45 side elevation of the machine, the same being partly in section; Fig. 3 is a plan view of the double eccentric which I employ to vary the movement of the lens block spindle; and Fig. 4 is a sectional elevation of the double eccentric.

Referring in detail to the parts—1 indicates a cast frame having the box-like base 2, the vertical standard 3 and the laterally 50 extending arm 4, all adapted for supporting the various parts of the machine. 5 indicates the main driving shaft mounted to extend vertically through the standard 3 of the frame, and at its upper end is a driving 55 pulley 6 adapted to be connected with any

suitable power, the pulley being coupled with the main shaft through a suitable clutch 7 adapted to connect or disconnect the pulley from the main shaft by manually operating a lever 8 mounted upon the frame. 60

9 designates the lower counter shaft mounted in bearings 10 and 11 within the base and the same is connected with the driving shaft by spiral gears 12 and 13.

14 is a vertical tool spindle mounted in 65 suitable bearings in the base and supported in a vertical direction upon an antifriction bearing 16. Tool spindle 14 has driven connection with the lower counter shaft 9 through spiral gears 17 and 18. In like 70 manner there is an upper counter shaft 19 mounted in bearings 20 and 21 upon the laterally extending arm 4 and having driven connection with the main shaft through spiral gears 22 and 23. 75

24 indicates the lens block spindle mounted to slide vertically in the direction of its axis of rotation in bearings at the outer end of the arm 4 of the frame, 25 being a spiral gear upon the counter shaft 19 meshing with 80 a spiral gear 26 adapted to drive the spindle 24, the latter being connected with the gear 26 by a feather or other suitable means to permit the spindle to slide freely through the gear 26 when raised or lowered by a lever 27 having a forked end 28 connecting with a loose collar 29 at the upper end of the spindle 24. 85

30 is a spiral compression spring surrounding the spindle 24 and seated at its 90 upper end against the outer end of the arm 4, the lower end of the spring pressing against a ring 31 adapted to serve as a raceway for balls 32, 33 being a ring serving as the lower raceway for the balls, and 34 is an 95 adjustable collar carried upon the spindle 24 and adapted to adjust the tension of the spring 30.

35 is a jointed swinging extension of the spindle 24, being connected therewith by a 100 universal coupling 36, 37 a sleeve or bearing having free sliding movement along the jointed spindle 35, 38 a chuck at the lower end of the spindle 35, 39 a driving pin held in the chuck and having universal connection with the lens block 40, the latter having the lens blank firmly cemented to its face, the blank being maintained in contact with the upper grinding face of the grinding tool by the tension of the spring 30. 105 110

41 is a toggle having jointed connection with the sleeve 37 at 42, and the inner end of the toggle is adjustably connected by means of a screw coupling 43 with a sliding 5 shaft 44 mounted to slide in a guide or lateral extension 45 integral with the frame, and 46 is an eccentric strap connected with the sliding shaft 44 at 47. Eccentric strap 46 is mounted upon an outer eccentric 48 10 which in turn is adjustable upon an inner eccentric 49 firmly secured to the main shaft, and a set screw 50 is employed to firmly lock the outer and inner eccentrics together.

51 is a tank adapted to contain a mixture 15 of abrasive material and any suitable liquid, and the same is supported upon an elevated shelf 52 upon the frame and has a vertical spindle 53 extending through the top, the spindle carrying a paddle to agitate the solution in the tank, rotation being imparted to the spindle 53 by a pulley 54, driven by a belt operating over a pulley 55 fixed upon the main shaft.

56 is a tube adapted to conduct the abrasive solution to the face of the grinding tool adjacent to the lens block, the supply of abrasive material being controlled by a valve 57. As the abrasive material escapes from the periphery of the grinding tool it is received by a pan 58 having a raised portion 59 in its bottom surrounding the tool spindle.

In assembling the machine the spindle which actuates the lens block is off-set as shown, being mounted out of alignment with the tool spindle. Power being applied to the machine, the tool spindle and the spindle carrying the lens block will both rotate in the same direction and at the same rate of speed, the spiral gears being proportioned

properly. As it is often desirable to vary 40 the stroke or swinging movement of the jointed lower portion of the lens block spindle, this is accomplished by adjusting the outer eccentric upon the inner eccentric, which operation varies at will the stroke of 45 the sliding shaft connecting with the lens block spindle. Thus the movement of the lens block in a radial direction over the face of the grinding tool may be varied from nothing to a maximum by adjusting the 50 outer eccentric upon the inner one.

What I claim is:—

In a lens grinding machine, the combination of a vertical main driving shaft, upper and lower horizontal counter shafts, a jointed lens block spindle slidable longitudinally, a coiled spring about the lens block spindle adapted to subject the same to tension, a tool spindle, spiral gearing to transmit motion from the main driving shaft to the tool spindle and also the lens block spindle, a sliding shaft operating transverse to the lens block spindle, a sliding sleeve upon the lens block spindle, an adjustable connection between the sleeve and the sliding shaft, an inner eccentric fixed upon the main driving shaft, an outer eccentric adjustable upon the fixed inner eccentric, and an eccentric strap mounted upon the outer eccentric and connecting with the sliding shaft, substantially as described.

In testimony whereof, I hereunto affix my signature, in presence of two witnesses.

WALTER K. ROGERS.
